Primary Examiner—Lucy Lieberman

(74) Attorney, Agent, or Firm—Nixon & Vanderhye P.C.

(57) **CLAIM**

The ornamental design for a watch, as shown and described.

DESCRIPTION

The sole view is a front, right side and bottom perspective view of a watch showing our new design.

The broken lines in the drawing are used to show portions of the watch that do not form part of the claimed design.

1 Claim, 1 Drawing Sheet
